UNITED STATES PATENT OFFICE

2,595,448

PORTABLE MILITARY BURNER UNIT

James L. Breese, Santa Fe, N. Mex., assignor to
 Breese Burners, Inc., Santa Fe, N. Mex., a corporation of Delaware

Application July 23, 1949, Serial No. 106,428

3 Claims. (Cl. 126—94)

1

My invention relates to an improvement in stoves or heaters.

One purpose is to provide a light weight portable stove adapted for camp or military use.

Another purpose is to provide a stove adapted to burn volatile fuels including gasoline.

Another purpose is to provide an improved burner assembly.

Another purpose is to provide an improved air supply means for burners of the type herein shown.

Another purpose is to provide a tent heater which includes a combined flue and tent support.

Other purposes will appear from time to time in the course of the specification and claims.

I illustrate my invention more or less diagrammatically in the accompanying drawings wherein:

Fig. 1 is a vertical section;

Fig. 2 is a section on line 2—2 of Fig. 1; and

Fig. 3 is a side elevation on a reduced scale, with parts disassembled.

Like parts are indicated by like symbols throughout the specification and drawings.

Referring to the drawings, 1 generally indicates any suitable floor or surface portion upon which the heater assembly is mounted; 2 indicates a normally fixed base structure which includes legs or supports 3, a circumferential reinforcing flange 4, and any suitable additional reinforcement 5. The base 2 rests upon the floor 1 and may be readily moved thereon, for proper positioning. Extending upwardly from the base 2 is a combined flue pipe and tent support 6. It is shown as closed at the bottom by the base 2 upon which it rests. It may receive at the top one or more reducer or extension elements of which the lowest is indicated at 7. It will be understood that the pipe 6 and the reducers 7 are of sufficient diameter to serve as flues for the below-described burner and are of sufficient height and strength to serve as a central tent support or pole.

Pivoted upon the normally fixed base 2 is the movable element generally indicated at 8. It may be supported, for example, upon a plurality of upstanding pivot members 9 with individual pivots 10. The members 9 are headed as at 11 and pass through the fixed platform 2. Springs 12 normally hold the parts in the position in which they are shown in Figs. 1 and 3, permitting, when necessary, some downward recession of the pivots 10. The member 8, as shown in Fig. 2, includes two opposite angles 14—15 connected

2

by a cross bar or rod 16 at the ends opposite the pivots. Through the rod 16 passes a U-shaped handle member 17 having end abutments 18 so proportioned that when the rod is in the position of Fig. 1 the abutments 18 elevate the supports 14 and 15. When the rod is rotated in the direction of the arrow of Fig. 1, and thus into the position into which it is shown in Fig. 3, the movable support 8 recedes downwardly to its position of Fig. 3. Wear plates 19 may be mounted on the fixed base 2 and provided with any suitable stops 20 against which the abutments 18 are positioned, over center, when it is desired to hold the support 8 in elevated position.

Supported on the flue structure 6 is a combustion chamber generally indicated at 25. It is shown as connected to the flue 6 by a cross flue or passage 26, located intermediate the ends of the combustion chamber 25. The combustion chamber may be of any suitable shape but it may conveniently be formed as a cylinder with a top element 27 which includes an upwardly convex intermediate portion 28 and a lower convex portion 29 of smaller diameter than the portion 28.

Secured to the otherwise open bottom of the combustion chamber 25, is a pot-like vaporizer 30 which includes a generally cylindrical circumferential wall and the bottom wall 31 centrally apertured as at 32, the aperture being surrounded by 30 the generally conic downwardly and inwardly extending flange 33. The circumferential side of the member 30 is provided with a plurality of primary air inlet apertures 34 shown as arranged at various distances from the ends of the vaporizer, and 35 circumferentially spaced thereabout. Above the highest of the primary air inlet apertures 34 I illustrate a single row of secondary air inlet apertures 35. These are shown as larger and more closely spaced than the air inlets 34, and as tilted

40 upwardly and inwardly toward the top of the vaporizer. The lowest row of primary air inlet apertures 34 may, if desired, be of somewhat larger diameter than the intermediate primary air inlet apertures. Preferably, the top of the 45 vaporizer is spaced from the bottom of the combustion chamber by a centrally apertured flame ring 36. It will be understood, as by inspection of Fig. 3, that the flue 6 constitutes a support for the combustion chamber 25 and the 50 vaporizer 30.

Removably supported on the member 8 is a fuel tank or generator indicated as 40 and having a bottom wall 41, a circumferential side wall 42, and a preferably upwardly domed top wall 43 apertured as at 44 in alignment with the aper-

ture 32 of the vaporizer bottom 31. The aperture 44 is preferably surrounded by a downwardly and inwardly turned flange 45 which, when the parts are in the position of Fig. 1, contacts and conforms to the opposed flange 33. It will be understood that when the generator 40 is positioned preferably upon the support 8 and the support 8 is then elevated to its position of Fig. 1 by rotation of the rod 16, the apertures 32 and 44 constitute together a single passage between the fuel container 40 and the interior of the vaporizer 30. The springs 12 maintain the parts snugly together and permit a reasonable variation in dimensions. 50 indicates an internal compartment or propagator within the larger generator 40; it is illustrated as tubular or cylindrical, as will be clear from Fig. 2. Its bottom may be open as at 51. It has a slot or slots 52 in its sides which extend from adjacent the bottom to adjacent the top of the tube or chamber 50. It is shown as having an inclined top wall 53 with a single outlet aperture 54. The chamber 50 is secured in place and supported within the fuel container 40 by means of the elbow member 55 and the transverse connecting pipe 56. The elbow 55 is suitably anchored on the top wall 43 as at 57 and it connects with an upwardly extending air inlet tube 58. The tube has a top closure 59 and an air inlet aperture 60 adjacent its upper end. 61 indicates a suitable bimetallic leaf or element which carries at its end a closure 62 of proper form and material completely to close the aperture 60 when the parts are in the position of Fig. 1. The bimetal 61 may be mounted on the upper bend 64 of the supporting rod or wire 63, which also may be employed to hold the cap or top closure 59 in place. 66 is a coil spring about the top rod portion 63 provided with an abutment 65, and formed and adapted to maintain a thrust against the upper end of the bimetal 61. It will be understood that the bimetal, in response to changes in temperature of the adjacent combustion chamber 25, is formed and adapted to warp into and out of closing position, in such fashion as to maintain and control a variable flow of air through the aperture 60. The bimetal may be adjustably set or limited by the threaded adjusting member 67 with its exterior manual handle 68.

When it is desired to use the burner or heater, the parts are positioned as shown in Fig. 1. However, the user may readily remove the generator and propagator unit for cleaning, refilling, etc., as shown in Fig. 3. It is also preferably removed to the position of Fig. 3 when the user wishes to light it. When it is so removed, however, unless it is about to be lighted, it is desirable to close the fuel receptacle 40, to prevent escape of vaporized fuel. When the parts are in the position of Fig. 3, the bimetal 61 will move to the closed position, thus preventing any flow of vaporized fuel through the air inlet 60. The user also may close the top aperture 44 by dropping the hinged closure 70 into place. The closure 70 with its arm 71 is pivoted as at 72 on any suitable collar or support 73 which surrounds a lower portion of the air inlet tube 58.

It will be realized that, whereas I have described and claimed a practical and operative device, nevertheless many changes may be made in size, shape, number and disposition of parts without departing from the spirit of my invention. I therefore wish my description and drawings to be taken as in a large part illustrative or diagrammatic rather than as limiting me to my precise showing. It will be understood, for ex-

ample, that the tent support feature may be omitted. It will be further understood that the method of raising or lowering and supporting the fuel container 40 may be widely varied.

5 The use and operation of my invention are as follows:

I provide a flexible unit of relatively small weight which can be easily handled and transported and which can be readily demounted. For 10 example, I have shown in Fig. 3, the fuel receptacle 40 may readily be removed. The tent support or adaptor and its upper parts may be readily removed, as they are shown as merely telescoped upon each other. The upper support 8 may be 15 removed by disconnecting the pivots 10. The result is a structure no component of which is of substantial weight or of too great size for easy handling.

With reference to the operation of the device, 20 the generator 40 may be filled to a level just below aperture 54 with a volatile fuel such as gasoline. Its closure 70 is swung to the position in which it is shown in Fig. 1 and the container is positioned upon and within the angles 14 and 15 of 25 the side support 8. Assume that it is first lighted. It will be understood that the flame passes upwardly through the apertures 44 and 32 and into the interior of the vaporizer 30 and the combustion chamber 25. Air flows inwardly through 30 the aperture 60 and along the tube 58 to the mixing chamber 50. The supply of air flows upwardly through the aperture 54 and also through the slot or slots 52 in the normal operation of the device. A primary mixture is provided by the air 35 flowing through the tube 58 and mixing with the vaporized fuel, the primary mixture flowing upwardly into the vaporizer or mixing chamber 30. The chamber 30, with its perforated walls, adds further primary air to the mixture, full combustion 40 taking place at or about the level of the secondary air inlets 35. The rate of combustion can be varied by the manual control 67, 68, which operates against the bimetal or warping bar 61.

In the use of my burner or tent heater the major 45 advantage is the method of lighting. The fuel tank or generator tank 40 is lighted first, when removed from the rest of the assembly. It need be lighted only in one place, in contrast to ordinary orchard heaters, where the generator may be lighted at the top, and a propagator tube must 50 also be lighted. After the generator has been lighted, it is moved into the position of Figure 1 and locked by the upward elevation of the support 8. I find it highly advantageous to employ 55 the offset stack herein described and claimed. The herein described thermostat arrangement is also highly efficient in use.

I claim:

1. In a stove, a base, a mixing and combustion 60 member supported by said base, said member having a bottom inlet, a flue therefor mounted on said base, to which said mixing and combustion member is connected, a generator tank removably supported on said base and having a top 65 outlet alignable with the bottom inlet of the mixing and combustion member, and means for moving the generator tank toward and away from a position in relation to the mixing and combustion member in which the inlet of the mixing and 70 combustion member is snugly engaged with the outlet of the generator tank.

2. The structure of claim 1 characterized in that the means for moving the generator tank and the mixing and combustion member toward 75 each other includes a support for the generator

tank, such support being hinged on the base, and means for rotating it upwardly and downwardly in relation to the base.

3. The structure of claim 1 characterized in that the means for moving the generator tank and the mixing and combustion member toward each other includes a support for the generator tank, such support being hinged on the base, means for rotating it upwardly and downwardly in relation to the base, and yielding take-up means between the base and the hinged support.
